BUILDING CONSTRUCTION

Anders Christian Olsen, Garden City, N. Y.

Application February 14, 1935, Serial No. 6,565

42 Claims. (Cl. 72—1)

This invention relates to building constructions and more particularly to partitioning and sheathing means for the interiors of buildings affording a complete covering and subdividing structure which may be applied either to finished interiors or, as original installations, to the framework of buildings under construction.

The general object of the invention is to provide a novel and improved construction of this character.

More specifically, it is an object of the invention to provide a partitioning and sheathing structure built up of panels of a suitable ornamental appearance and durable composition, the panels being secured together and supported from the wall and ceiling base structures, and connected with corresponding assemblies in the partition arrangements, by novel connecting and spacing elements, the provision of which constitutes another important feature of my invention.

In its preferred embodiments the invention contemplates the provision of certain cooperating fastening members which are adapted to be engaged by the panels themselves on the one hand, and by the spacing, supporting or hanger elements on the other, whereby these members or modifications thereof may be employed in similar arrangements of ceiling, wall or double partition structures. In certain embodiments of the invention the panels are kerfed for the insertion of portions of the fastening elements, and in all cases the cooperating fastening elements interlock by means of somewhat similarly kerfed or tongue-and-groove portions.

Other features of the invention include the provision of various elements, combinations and subcombinations of elements for securing the partitions and sheathings to the floor and ceiling, as well as the provision of cornice, window, baseboard, chair-rail, and other ornamental and practical finishing constructions.

Further objects and features of novelty will be apparent from the following specification when read in connection with the accompanying drawings in which certain embodiments of my invention are set forth by way of example.

In the drawings:

Figure 1 is a somewhat diagrammatic perspective view of a portion of a building interior structure, on a smaller scale than that of subsequent figures and showing wall and ceiling sheathing and a partition assembly embodying the principles of my invention;

Figure 2 is a vertical sectional view of the partition illustrated in Figure 1, but on a larger

scale and showing more detail;

Figure 3 is a fragmentary perspective view of the same partition with portions shown in cross section and other portions broken away for the sake of clearness;

Figure 4 is a fragmentary horizontal sectional view of the partition taken on line 4—4 of Figure 1;

Figure 5 is a fragmentary horizontal sectional view of the wall sheathing taken on line 5—5 of Figure 1;

Figure 6 is a vertical sectional view of the lower portion of the wall sheathing taken on line 6—6 of Figure 1;

Figure 7 is a fragmentary plan view of a partially completed ceiling construction forming one embodiment of my invention in which the panels, may have certain acoustic properties;

Figure 8 is a fragmentary view in perspective of a portion of this ceiling structure;

Figure 9 is a cross sectional view taken on line 9—9 of Figure 7;

Figure 10 is a cross sectional view taken on line 10—10 of Figure 9;

Figure 11 is a fragmentary perspective view of one end of one of the cross strips of substantially T-shaped cross section forming a part of the panel supporting structure;

Figure 12 is a fragmentary perspective view of a partially completed suspended ceiling structure also of the built-up panel type and which may also have acoustic properties;

Figure 13 is a cross sectional view of this ceiling structure;

Figure 14 is a fragmentary vertical sectional view of a modified form of double wall partition similar to that shown for example in Figure 2;

Figure 15 is a fragmentary horizontal sectional view of the same embodiment;

Figures 16 and 17 are detail sectional views of modified forms of panel joints which may be employed in practicing my invention;

Figure 18 is a fragmentary vertical sectional view of the base of another form of partition;

Figure 19 is a fragmentary horizontal sectional view taken on line 19—19 of Figure 18;

Figure 20 is a vertical sectional view of a variant form of partition;

Figure 21 is a view in horizontal section of a portion of a window frame disposed in a double walled partition and taken on a line corresponding to line 21—21 of Figure 1;

Figure 22 is a broken perspective view of still another partition modification;

- Figure 23 is a horizontal sectional view of a similar partition which embraces a pillar;
- Figure 24 is a horizontal sectional view of another partition spacing and supporting means;
- 5 Figure 25 is a fragmentary perspective view of a further modification of partition structure;
- Figure 26 is a perspective view showing a wall sheathing connection;
- 10 Figure 27 is a perspective view partly in section of a ceiling sheathing suspension;
- Figure 28 is a partial perspective view of a further modification showing partition assembly; and
- 15 Figure 29 is a partial perspective view showing a portion of the junction of a wall sheathing and a ceiling sheathing, and also disclosing an appropriate cornice structure.
- The perspective view of a portion of the interior of a building shown somewhat diagrammatically in Figure 1 may be taken as a key figure upon which many of the subsequent figures of drawing may be based. This figure illustrates generically the various adaptations of my invention to ceiling, wall sheathing and partition structures; this entire assemblage of interior construction being characterized by the embodiment of certain more or less standard elements comprising panel supporting, spacing, tying and hanging devices.
- 30 The wall supporting structure is indicated in the drawings by the reference character 10 and as already pointed out may be a rough masonry construction, a finished wall as, for example, in the case of the application of my invention to an old building, or it may represent the framework including risers and other more or less skeleton-like elements of a partially completed building.
- The ceiling supporting structure is indicated in this example by the joists 11, but of course may 40 be in practice any form of overhead structure. The wall sheathing is indicated generally by the reference character 12 and the suspended ceiling construction has the reference character 15 applied thereto. Both of these sheathing assemblies are preferably of the built-up panel type and the wall sheathing 12 is connected to the base wall 10 by means of suitable spacing and supporting elements which will be later described. One means of suspending the ceiling sheathing 50 15 from the joists 11 is suggested at 16 and may take various specific forms as set forth in subsequent descriptions.
- A double walled partition assembly is indicated generally at 20 and the separate spaced walls 55 thereof are connected together by means shown in more detail in subsequent figures. Both the wall sheathing assembly 12 and the partition construction 20 are comprised of panels of suitable size and shape such as indicated at 21 and may 60 be provided with suitable ornamental and useful embellishments such as the baseboards 22, the chair-rails 23, the molding or ceiling cornice 24 and the window assembly 25. A door 26 is suggested in Figure 1 as giving access to the room.
- 65 The details of various embodiments of the structures shown diagrammatically in Figure 1 may be found in various subsequent views, many of which are taken on the section lines indicated upon this guide figure.
- 70 One of the preferred forms of double walled partition structure embodying the principles of the invention is very clearly illustrated in Figures 2, 3, and 4 of the drawings. Suitably secured to the floor structure 28 as by means of a fastening 75 screw 29 is the channel shaped floor track or
- seating member 30. The upturned flanges 31 of this member may conveniently be received within the kerfs 32 formed in the bottom edges of the opposite baseboard members 22. The upper edges of the baseboards 22 are similarly kerfed at 33. The superposed panels 21, which are preferably, though not necessarily, of hard asbestos or tile composition, and the chair-rail member 23 on each side of the partition are also kerfed in the manner indicated by the numerals 5 33. Between adjacent edges of the panels and corresponding covering elements are disposed the substantially T-shaped securing members 35 which are provided with flanges 36 facing in opposite directions and adapted to enter the kerfs 10 33 formed in the meeting edges of the panels. These members or strips 35 may conveniently be made of folded sheet metal as illustrated.
- A preferably H-shaped spacing and supporting frame is designated generally by the reference character 38 and comprises the upright members or posts 40 which in this embodiment comprise the mating angle irons 41 with which the ends of the panel connecting strips 35 are interlocked. Between the inwardly directed flanges of the 25 posts 40 the spacing or tie elements 45 are disposed and rigidly secured as by welding.
- The means for securing the strips 35 to the posts 40 comprises a further kerfed or tongue-and-groove connection. The folded horizontal 30 portion of the strips 35 are kerfed at their ends as at 47 to snugly receive the outwardly directed flanges 42 of the angle irons 41. The ends of these strips 35 preferably terminate before abutting each other. The vertical mating edges of 35 certain of the panels 21 which occur adjacent the supporting means 38 may be kerfed in a manner similar to that shown at 33 to receive a spline strip 48.
- At the top of the partition structure which has 40 just been described, a member 50 is provided which forms a cornice or molding strip for positioning the upper end of the partition and securing it to the ceiling 15 or the like. This member 50 may be of sheet metal which comprises the 45 flat plate 51 secured to the ceiling as by means of the screws 52 and having secured to its side edges as at 53 the downwardly and inwardly inclined portions 55 which may have the upwardly turned flanges 56 at their edges for embracing 50 the partition assembly. It is conceivable that the portions 55 may be adjustably secured to the plate 51 so that the member 50 may be expanded or contracted to receive partition assemblies of 55 various thicknesses.
- The preferred method of assembling the panels is to first set up the H-shaped supporting and spacing members 38 within the floor track 30 which has already been laid along the desired line of partition. Then the baseboards 22 may 60 be applied to the floor track and the successive tiers of panels 21 (and chair-rail 23 if desired) are fitted to the next lower tiers and secured to the members 38 by means of the connecting and supporting strips 35. The uppermost row of 65 panels 21 is first inserted beneath the depending molding strip 55 and then lowered into position upon the underlying strips 35.
- The method and means of assembling the wall sheathing structure 12 will now be described. As 70 clearly shown in Figure 6, a channel member 68 is secured to the floor 28 and disposed closely adjacent the wall 10 with one of its upturned flanges 61 in contact therewith. The opposite flange at 75 62 contacts with the baseboard 22 which may be 75

installed just as indicated in Figure 2 of the drawings in connection with the partition structure, or may be varied as suggested in Figure 6 by the provision of an upwardly projecting flange 64 adapted to enclose the lowermost tier of panels 21. The successive tiers of superposed panels 21 are kerfed and connected by strips 35 just as in the case of the previously described embodiments. However, these strips 35 are secured at their ends to vertical studs 65 which are the counterparts of the posts 40 of the partition supporting members 38. These studs or posts 65 may conveniently be formed in the same manner as the panel edge supporting strips 35 having overlapping body portions and outwardly flared flanges of somewhat heavier construction. The floor track elements 60 will rigidly secure the posts or studs 65 to the floor and any suitable molding or cornice device indicated generically at 24 in Figure 1 may be employed to fasten the upper end of the wall sheathing assembly. This molding may follow the general type indicated at 50 in connection with the partition structure.

In Figures 16 and 17 of the drawings there are shown certain embodiments of overlapping panel constructions. The panel designated 21a is provided with an offset flange 67 which overlies the upper edge of the lower row of panels. The adjacent edges of panels 21b are both provided with overlapping flanges 68 which lie within the boundary planes of the panels. The same sort of supporting strips 35 may be employed in this connection or the spline strips 48 as shown in Figure 4 may occur at points of this description.

In Figures 14 and 15 there is shown an adaptation of the present invention in which certain box-like sheet metal members are employed which have been used in other connections in certain of my prior applications. In this embodiment these box-like elements, designated by the reference character 70, comprise a hollow tubular body portion 71 from one of the side walls of which the parallel flanges 72 extend to form a block letter T. The outer edges of these flanges 72 are provided with flaring wings 73, which if desired may be of a slight ogee configuration and of a resilient construction in order to clamp certain other portions of the partition structure between these wings and the body portion 71 of the element 70. A spacing and connecting clip 75 serves to join the two posts 70 at intervals along their lengths to provide another embodiment of the substantially H-shaped partition supporting element disclosed in another form at 38 in Figure 2. The connecting clips 75 are provided with narrow necks 76 adjacent their extreme ends and with the substantially T-shaped heads 77. The heads 77 are received within the hollow body portion 71 of the posts or studs 70, the neck portion 76 extends between the parallel walls or flanges 72, and shoulders 78 on the clip abut the outer surfaces of the flared wings 73.

In order to secure the panels 21 to this partition stud the strips 35' are used. These strips are very similar to the strips 35 described in connection with the other embodiments, but are provided with a considerably wider kerf 47' to receive the sides of the box-like body portion 71 of the strip 70. The strips 35' are provided with the outwardly flaring flanges 36 as in the other case which interfit with the adjacent kerfed edges of the panels 21. In order to prevent the clip 75 from twisting and becoming dislodged from its proper position, a tongue 79 is struck from the center of the clip 75 and bent at an angle with the

main portion thereof so as to enter the space between the flanges 72 of the member 70 at a point which is spaced from the position of the adjacent neck 76.

One of the preferred forms of ceiling assembly also makes use of these box-like strips or members 70 in conjunction with the other interlocking members just described. This ceiling adaptation is illustrated very clearly in Figures 7-11 inclusive of the drawings.

In this embodiment, the panels designated by the numerals 21 as in the other embodiments may be of the acoustic type, being formed of suitable sound absorbing material such as mineral wool or the like, or on the other hand they may be made of the hard asbestos composition preferred in connection with the other embodiments. They may also be provided in any desired shape other than the square type illustrated and are preferably, although not necessarily, provided with chamfered or bevelled edges as shown.

As most clearly shown in Figures 8 and 9 of the drawings, headed hanger units 16 are secured to the joists 11 and are adapted to depend therefrom with their lower ends in substantially the same horizontal plane. These hanger units are arranged in rows extending across the room, and their headed ends 81 are adapted to interlock with the longitudinal supporting strips which, being the counterparts of the corresponding strips 70 in the position illustrated in Figures 14 or 15, may be given the same reference character. The body portions 71 of these strips are each of a box-like configuration and provided with the upwardly extending spaced walls 72 and the laterally flared wings or flanges 73. The hanger units 16 may be applied to the longitudinal strips by inserting the headed ends flatwise through the slots formed between the walls 72 and then rotating the units through an angle of 90° until the headed ends 81 extend laterally across the interior of the box-like body portion of the longitudinal strips, whereupon the members 16 may be nailed or otherwise secured to the joists or other convenient portions of the framework of the building. As will be readily understood, the hanger members 16 may be applied to the strips 70 at any point along their length so as to obviate any difficulty which might arise due to the unequal spacing of the joists or other supporting members.

The ceiling tiles or panels 21 are suspended by the T-shaped cross strips 35' which have already been described in connection with the partition structure shown in Figures 14 and 15. These cross strips are adapted to be applied to the adjoining edges of adjacent panels in each row of panels which lie between the parallel longitudinal strips 70.

The flat body portions of the strips 35' are adapted, when installed, to occupy vertical planes and at their ends are formed with the kerfs 47' within which are adapted to be received the laterally extending body portions 71 of the box-like T strips 70. This connection is exactly the same as that illustrated in Figures 14 and 15 which shows a similarly assembled partition structure. At the lower edge of the main portion of these cross strips there are formed laterally extending wings or flanges 36 which are adapted to enter the kerfs or slots 33 provided in the edges of the tiles or panels.

In constructions in which acoustic tiling or other panels made of relatively soft material are used, the kerfs or slots 33 need not be preformed

as in the case of hard tiles, and the relatively sharp edges of the flanges 27 of the cross strips may be pressed into the sides of the panels during the erection of the ceiling. Between the adjacent edges of certain of the panels there may be inserted baffle or spline strips 48 as in the partition construction shown in Figure 4.

In applying the covering structure to the supporting means which comprises the hangers 16 and longitudinal strips 70, a cross strip 35' is placed in position with the kerfs 47' receiving the side portions of the body members 71 of the strips 70, as already described, and one of the tiles 21 may be pressed into engagement with one of the flanges 36 of the strip 35' until the flange is firmly seated or embedded within the material of the tile. The next cross strip 35' is then applied to the adjacent longitudinal strips 70 and is slid along the supporting ledges on the strips until one of the flanges 36 is embedded in the edge of the panel 21 or received within the kerf 33. The next panel is then applied to the last mentioned cross strip in the same manner as before, and these operations are continued until a complete row of panels is assembled. Succeeding rows of panels are similarly built up until the ceiling is completely covered.

Although especially adapted for the use of acoustic tiling or other varieties of tile composed of relatively soft material into which the flanges of the cross strips may be embedded by the application of slight pressure, it is readily apparent that tiles or panels of harder material may be employed, in which case the kerfs 33 for the reception of these flanges must be formed before assembly of the ceiling.

In Figures 12 and 13 a modified type of acoustic ceiling is illustrated which, however, employs substantially the same supporting means. From the overhead supporting structure 11 the headed hangers 16 depend and serve to support the box-like T-shaped strips 70 to provide the main supporting assembly. In this embodiment the panels 121 take the form of pans comprised preferably of sheet metal and adapted to contain fibrous or other acoustic material for sound insulation purposes. The margins of these panels 121 are turned upwardly as at 135 and are provided at their ends with kerfs 147 adapted to receive the lateral body portions of the box-like T strip 70. Narrower end flanges 80 may be struck up from the panels 121 to isolate the interiors of the pan-like panels if this is desired. It will thus be seen that the panel flanges 135 are the practical equivalents of the edge supporting strips 35 and 35' described in connection with other embodiments.

In Figure 26 a modification of a wall sheathing structure is illustrated. In this embodiment a box-like strip 85 preferably rectangular in cross section and provided with a slot 86 in one of its longer walls is employed as a spacing element similar in its function to the member 65 shown in Figures 5 and 6. The box-like T-shaped strip or post 70 is made use of in this embodiment in supporting the edges of the panels 21, the latter being received within the slots provided by the lateral extensions of the body portions 71 and the flaring wings or flanges 73. At the intersection of each of the strips 70 and 85, which are preferably disposed at right angles with each other, a securing means such as a nail or spike 88 is provided. The securing element is adapted to pass through the slot 87 between the parallel walls 72, forming the upright of the T of the member 70

and then through a perforation in the rear wall of the body portion 71, then through the slot 86 in the other strip and finally through a perforation in the rear wall of this latter element and into the basic wall supporting structure. The head 89 of the fastening element rests against the flanges 73 and bridges the slot 87. A suitable finishing coating such as plaster may be applied to the surface of this wall sheathing assembly if desired.

Another partition modification is shown in Figures 18 and 19 in which use is made of the various T-shaped supporting and spacing members already described. A floor strip or track 30 is provided in this embodiment to retain the H-shaped posts 38' which comprise in this instance the two channel members 90, the body portions of which are of a trussed or skeleton formation as indicated clearly in Figure 18. The oppositely extending end flanges of these channel members 90 are indicated at 91 and are the equivalents of the T-shaped portions 40 of the spacing and connecting assemblies shown in Figures 2, 3, and 4 of the drawings. Extending transversely of these vertical supporting and spacing members 38' are the hollow T-shaped strips 70 which have their wing flanges 73 contacting the flanges 91 of the posts 38' and securely tied to the opposite corresponding strip 70 by means of the cross tie clip 95. This strip is provided with heads 96 at each of its ends which are adapted to enter the hollow body portion 71 of the strip 70 and thus interlock with these members. The panels 21 in this instance are secured to the body portion 71 of the T-shaped strip 70 by any suitable fastening means as, for example, the screws 97. Suitable molding 35 or trim elements 98 may also be provided at the floor junction.

In Figure 20 the H-shaped supporting strip with the T-shaped end members is substantially identical with that employed in Figure 2 of the drawings and will be given the same reference character 38. The cross strips 70 are applied thereto by means of the tie clips 95 exactly as in the case of the partition illustrated in Figures 18 and 19. However, the panels 21 are received within the kerfs or slots formed between the body portions 71 of the strip 70 and the wings 73 and a coating of plaster 99 is laid over the panels 21 and enclosing the strips 70.

In the partition illustrated in Figure 21, the skeleton supporting and spacing members 38' are employed but the T-shaped end portions 90 are adapted to enter the body portions 71 of the box-like T-shaped strips 70 and so interlock therewith. The panels 21 are received within the slots 55 as in the example shown in Figure 20 and a covering 100 of plaster or additional panel units may be applied. A window frame or jamb member 101 which may also be formed of hard asbestos paneling or other suitable material is applied at the end 60 of the panel and is adapted to surround the window opening shown in Figure 1 of the drawings, Figure 21 being taken on line 21-21 of that figure. Box-like strips 103 which are somewhat similar to those designated 70 except for the flaring wings 73 are adapted to receive the glass pane 105 and may be provided interiorly with a resilient cushion strip 106.

In Figure 22 the box-like T strips 70 are adapted to receive the panels 21 behind the flanges 73 in the same manner as shown in Figures 20 and 21, while the heads 96 of the tie clips 95 are received within the body portion 71 of the strip 70. In this case, the entire construction depends solely 75

upon the clips 95 for spacing and supporting functions.

In Figure 23 there is shown an arrangement whereby the partition illustrated in Figure 22 may be carried around a pillar such as indicated at 110 wherein the pillar is of a greater diameter than the interior space of the partition. The strips 70 of the nearest tying elements upon either side of the pillar 110 are interlocked with additional strips 70 by insertion of the body members 71 within the slots provided by the wings 13 of adjacent members as shown at 111. As many of these stepped strip connections are provided as is necessary to surround the pillar and will naturally vary with the diameter of the pillars encountered. The two strips 70 at the wider portion of the pillar may be connected by the short panel member 112 as clearly shown in Figure 23.

In Figure 24 the opposite panel supporting strips 70 are connected by a solid plate 115 which may be of any length and which is adapted to enter the slot 87 between the walls 12, and also the body portion 71 of the strips in which it is keyed by means of the retaining element or cotter 116.

In Figure 25 the panel edge supporting box-like T-shaped strips 70 are reversed and provided in their wider walls with relatively large openings 117 through which the spacing clips 95 are adapted to extend, the heads 96 of the clips resting upon the outer faces of the outwardly turned wings 73 of the strips. The irregularities provided by the slots 87, the wings 73, and the heads 96 provide excellent keying means for the plaster coating 99.

In Figure 28 the panel edge supporting strips 70 are adapted to receive the panels 21 and are spaced by means of the skeleton assemblies 38' just as shown in Figure 21. In order to prevent relative movement of the T-shaped ends 90 of the members 38' within the body portion 71 of the strips 70, the flanges 91 are bent so as to provide the distorted offset portions 120 as shown, the amount of offset, of course, being equal to the width of the interior of the box-like body portion 71.

In Figure 27 a ceiling construction is illustrated which is the exact counterpart of one half of the partition arrangement shown in Figure 25, the hangers 16 taking the place of the spacing and tying clips 95. Strips 70 are provided with the openings 117 through which the hangers 16 extend and the heads 81 of the hangers underlie the flanges 73 and provide additional keying means for the plaster 99.

In Figure 29 there is shown a ceiling cornice element 125 which is provided with the curved portion 126, the upper and lower right angle portions 127 and the substantially U-shaped panel enclosing portions 128. These latter portions receive the ceiling and wall panels 21 in the same manner that the strips 70 function.

It will be understood that various changes and modifications may be made in the embodiments illustrated herein both in the manner of arranging the various elements disclosed, many of which may be considered standardized forms with respect to this invention; and also changes in the material employed may be effected without departing from the scope of the invention as defined in the following claims.

Having thus described the invention, what is claimed as new and desired to be secured by Letters Patent is:

1. An interior covering structure for buildings

comprising, in combination, spaced wall and ceiling members, at least the exposed ones of which are composed of a plurality of panels, spacing and connecting elements between said spaced wall and ceiling members comprising elongated main supporting member substantially T-shaped in cross section, other elongated members also T-shaped in cross section interlocked with said first named members and with the margins of adjacent panels.

2. An interior covering structure for buildings comprising, in combination, spaced wall and ceiling members, at least the exposed ones of which are composed of a plurality of panels, spacing and connecting elements between said spaced wall and ceiling members comprising elongated main supporting members substantially T-shaped in cross section, other elongated members also T-shaped in cross section having interlocking tongue-and-groove connections with said first named members and with the margins of adjacent panels.

3. An interior covering structure for buildings comprising, in combination, spaced wall and ceiling members, at least the exposed ones of which are composed of a plurality of panels, spacing and connecting elements between said spaced wall and ceiling members, the edges of said panels being kerfed, panel edge supporting members having portions entering the kerfs in said panel edges and other portions themselves kerfed for the reception of portions of said connecting and spacing elements.

4. In an interior structure of the type described, spaced wall assemblies of the built-up panel type, supporting and spacing members of substantially H-shaped cross section disposed between said wall assemblies, each of the arms of said H-shaped strip disposed adjacent one of the respective wall assemblies, and panel edge supporting strips connected with the arms of the H-shaped members and with certain of the adjacent edges of the panels.

5. In an interior structure of the type described, spaced wall assemblies of the built-up panel type, supporting and spacing members of substantially H-shaped cross section and panel edge supporting strips of T-shaped cross section connected by their upright portions with the arms of the H-shaped members and having their arms interlocked with certain of the adjacent edges of the panels.

6. In an interior structure of the type described, spaced wall assemblies of the built-up panel type, spacing and connecting means between said spaced wall assemblies, said means comprising main supporting members substantially T-shaped in cross section associated with each assembly, corresponding T members of the opposite assemblies being connected by cross tie elements, panel edge supporting strips also T-shaped in cross section, the upright or shank of said T-strips being interlocked with the cross portion of the T-shaped main members, and the cross portions of the T-shaped strips interlocking with the panel edges.

7. In an interior structure of the type described, spaced wall assemblies of the built-up panel type, spacing and connecting means between said spaced wall assemblies, said means comprising main supporting members substantially T-shaped in cross section comprising hollow box-like strips associated with each assembly, corresponding T members of the opposite assemblies being connected by headed cross tie

- elements which enter said box-like strips, T-shaped panel edge supporting strips, the upright being interlocked with the cross portion of the T-shaped main members, and the cross portions 5 of the T-shaped strips interlocking with the panel edges.
3. In an interior structure for buildings, spaced wall assemblies, hollow sheet metal double cornice members secured to the ceiling and opening 10 downwardly to receive the upper portions of said wall assemblies, said cornice members being laterally extensible to accommodate wall assemblies of various thicknesses and spacings, the downwardly opening portions of said cornice being of 15 sufficient extent to conceal any gap or clearance between the upper edge of said wall assembly and said ceiling.
9. In a wall assembly of the built-up panel type, a plurality of panels, a portion of the adjacent 20 edges of certain of said panels adapted to abut each other and other portions to overlap adjoining panels, and panel supporting strips having portions embedded within the abutting edges of 25 said panels and thus adapted to interlock with said abutting portions.
10. A partition structure for buildings comprising, in combination, spaced wall assemblies of the built-up panel type, including panel edge supporting strips, main wall supporting members 30 comprising elongated hollow box-like substantially T-shaped strips, the foot or base of each T being open, headed, tie elements connecting corresponding main wall supporting members, the heads of said elements adapted to enter the hollow 35 low T members.
11. A partition structure for buildings comprising, in combination, spaced wall assemblies of the built-up panel type, including panel edge supporting strips, main wall supporting members comprising 40 elongated hollow box-like substantially T-shaped strips, each having oppositely flaring flanges at the open base of the upright portion of the T, headed tie elements connecting corresponding main wall supporting members, the heads of said 45 elements adapted to enter the hollow T members, narrow necks on the connecting elements adapted to occupy the uprights of the T member and shoulders on the intermediate portions of said connecting elements adapted to abut said flaring flanges.
- 50 12. A partition structure for buildings comprising, in combination, spaced wall assemblies of the built-up panel type, including panel edge supporting strips, main wall supporting members comprising elongated hollow box-like substantially T-shaped strips, the foot or base of each T being open, headed tie elements connecting corresponding main wall supporting members, the heads of said elements adapted to enter the hollow 55 T members, and tongues struck from the intermediate portion of said connecting element and adapted to enter the upright portion of one of said T members at a point spaced from the point at which the corresponding head of said connecting element enters, whereby rotation of said connecting element about its longitudinal axis is prevented.
13. In an interior structure for buildings, a 60 suspended ceiling construction comprising a plurality of panels arranged in substantial edge to edge relationship, substantially T-shaped panel edge supporting strips having their heads interlocked with certain of the edges of said panels, elongated substantially T-shaped main supporting 65 members extending transversely of said first
- named strips and suspended by hangers from the overhead supporting structure of the room, the ends of said panel edge supporting strips interlocking with said main supporting members.
14. In an interior structure for buildings, a suspended ceiling construction comprising a plurality of panels arranged in substantial edge to edge relationship, substantially T-shaped panel edge supporting strips having their heads embedded in certain of the edges of said panels, elongated substantially T-shaped hollow box-like main supporting members extending transversely of said first named strips, headed hangers secured to the overhead supporting structure of the room and adapted to enter said hollow box-like members 15 and interlock therewith, the ends of said panel edge supporting strips interlocking with said box-like main supporting members.
15. In an interior structure for buildings, a suspended ceiling construction comprising a plurality of panels arranged in substantial edge to edge relation, adjacent edges of said panels being kerfed, panel edge supporting strips having flanges entering said kerfs, elongated hollow box-like main supporting members extending transversely of said strips and suspended from the overhead supporting structure of the room, the ends of said strips being themselves kerfed and adapted to interlock with said hollow box-like main supporting members.
16. In an interior construction for buildings, in combination, a covering structure for the walls and ceiling thereof comprising a plurality of pre-fabricated panels of relatively soft material, a plurality of supporting strips, flanges formed on 20 said strips and embedded in the material of which the panels are composed at the edges of said panels by pressing said flanges into said material, and suspension means for said supporting strips.
17. In an interior structure for buildings, a suspended ceiling construction comprising a plurality of elongated main supporting members, hangers interlocking therewith and supporting said members from the interior framework of the room, panels provided with turned up edge flanges, the 25 ends of said flanges provided with kerfs for interlocking with said main supporting members.
18. In an interior structure for buildings, a suspended ceiling construction comprising a plurality of elongated main supporting members having hollow box-like body portions, hangers interlocking with said hollow body portions and supporting said members from the interior framework of the room, panels provided with turned up edge flanges, the ends of said flanges provided with kerfs for interlocking with the box-like body 30 portions of said main supporting structure.
19. In an interior structure for buildings, a wall sheathing assembly comprising a plurality of panels arranged in edge to edge relation, substantially T-shaped panel edge supporting strips interlocking with said panel edges, similar T-shaped main supporting and spacing members having their head flanges interlocking with the ends of said first named panel edge supporting strips and having the base edges of their upright members 35 adjoining the interior wall framework of the room.
20. In an interior structure for buildings, a wall and ceiling sheathing assembly comprising a plurality of panels arranged in substantially edge to edge relation, panel edge supporting strips comprising hollow box-like members each substantially T-shaped in cross section and having flaring wings at the base of the upright of the T, 40

- the panel edges being received between said wings and the hollow head flanges, the hollow head portion adapted to face inwardly toward the framework of the room and provided at intervals with 5 openings in the outer surface thereof, headed fastening elements adapted to pass through the hollow upright portion of the T and to extend through said openings, the head of said elements adapted to overlap and rest upon said flaring 10 wings.
21. In an interior structure for buildings, a wall and ceiling sheathing assembly comprising a plurality of panels arranged in substantially edge to edge relation, panel edge supporting strips 15 comprising hollow box-like members each substantially T-shaped in cross section and having flaring wings at the base of the upright of the T, the panel edges being received between said wings and the hollow head flanges, the hollow head portion 20 adapted to face inwardly toward the framework of the room and provided at intervals with openings in the outer surface thereof, headed fastening elements adapted to pass through the hollow upright portion of the T and to extend 25 through said openings, the head of said elements adapted to overlap and rest upon said flaring wings, and a hollow box-like strip disposed between said first named strip and the room framework and extending substantially transversely of 30 said first named strip for spacing the sheathing from the wall structure.
22. In an interior structure for buildings, a partition construction comprising spaced wall assemblies of the built-up panel type, panel supporting strips extending at intervals along said wall assembly, partition supporting and spacing members comprising skeleton-like channel elements, the corresponding panel supporting elements of opposite wall assemblies adapted to abut 35 the flanges of said spacing members and secured together by headed tie elements.
23. In an interior structure for buildings, a partition construction comprising spaced wall assemblies of the built-up panel type, panel supporting strips extending at intervals along said wall assemblies, H-shaped partition supporting and spacing members comprising skeleton-like channel elements, the corresponding panel supporting elements of opposite wall assemblies 40 adapted to abut the flanges of said spacing members and secured together by headed tie elements, said panel supporting strips being of a hollow box-like construction, and said tie elements provided with heads adapted to interlock therewith.
24. In an interior structure for buildings, a partition construction comprising spaced wall assemblies of the built-up panel type, hollow box-like panel edge supporting strips of substantial T-shaped cross section, H-shaped trussed members 45 having the upright portions of the H disposed within the hollow interiors of said panel edge supporting strips and certain of their flanges being distorted in order to substantially fill the interiors of said strips to prevent relative movement of 50 said H-shaped members and the panel edge supporting strips.
25. An interior structure of the type described, spaced wall assemblies of the built-up panel type, supporting and spacing members of substantially 55 T-shaped cross section, H-shaped partition supporting and spacing members comprising channel elements, the corresponding panel edge receiving and supporting members of opposite wall assemblies adapted to abut the flanges of said 60 spacing members and secured together by headed 65 strips.
26. In an interior structure for buildings, a partition construction comprising spaced wall assemblies of the built-up panel type, each including hollow box-like panel edge receiving and supporting strips of substantially T-shaped cross section, the feet of the T strips opening inwardly of 70 the partition and provided with flaring wings, tying and spacing elements provided with heads and narrow necks at each end thereof, said heads and necks adapted to occupy the hollow interior of said panel edge supporting strips and shoulders provided adjacent said necks for abutting said flaring wings.
27. In an interior structure of the type described, a partition construction comprising spaced wall assemblies of the built-up panel type, panel edge receiving and supporting strips associated with each wall assembly and connected with corresponding strips of the opposite assembly by headed tie elements, said tie elements being provided with heads interlocking with said strips, means for widening said partition as for the purpose of surrounding a pillar or other structure comprising a plurality of similarly shaped strips interlocking with each other and arranged in stepped relation about said pillar or the like.
28. In an interior structure of the type described, spaced wall assemblies of the built-up panel type, spacing and connecting means between said spaced wall assemblies, said means comprising substantially T-shaped main supporting members comprising a pair of angle shapes associated with each assembly, corresponding T members of the opposite assemblies being connected by cross tie elements, T-shaped panel edge supporting strips formed of folded sheet metal having the upright of the T doubled and oppositely extending wings flaring therefrom, the upright of the T being interlocked with the cross portion of the T-shaped main members, and the cross portions of the T-shaped strips interlocking with the panel edges.
29. In an interior structure of the type described, a partition construction comprising spaced wall assemblies of the built-up panel type, panel edge supporting strips of a hollow box-like construction and of substantially T-shaped cross section, connecting and spacing plates having their edges received within the interior of said strips, and keys passing through said edges for retaining said plates within said strips.
30. An interior covering structure for buildings comprising, in combination, spaced wall and ceiling members, at least the exposed ones of which are composed of a plurality of panels, spacing and connecting elements between said spaced wall and ceiling members comprising elongated main supporting members substantially T-shaped in cross section, the edges of said panels being kerfed, panel edge supporting members also being substantially T-shaped in cross section and having certain of their arms inserted in the kerfs in said panel edges and other portions of said supporting members being themselves kerfed for the reception of portions of said T-shaped connecting and spacing elements.
31. In an interior structure for buildings, a wall covering structure comprising a plurality of panels arranged in substantially edge to edge relation, adjacent edges of said panels being kerfed, panel edge supporting strips having

flanges entering said kerfs, elongated hollow box like main supporting members extending transversely of said strips and secured to the interior wall framework of the room, the ends of said strips being themselves kerfed and adapted to interlock with said hollow box like main supporting members.

32. In an interior structure of the type described, spaced wall assemblies of the built-up panel type, spacing and connecting means between said spaced wall and ceiling members, said means comprising substantially T-shaped main supporting members comprising a pair of angle shapes associated with each assembly, corresponding T members of the opposite assemblies being connected by cross tie elements, T-shaped pannel edge supporting strips, the upright of the T being interlocked with the cross portion of the T-shaped main members, and the cross portions 20 of the T-shaped strips interlocking with the panel edges.

33. In an interior structure for buildings, a partition construction comprising, in combination, spaced wall assemblies of the built-up panel type each including a plurality of panels arranged in substantially edge to edge relation, and panel edge supporting strips each comprising a hollow box like member substantially T-shaped in cross section and having flaring wings at the base of the upright of the T, the panel edges being received between said wings and the hollow head flanges, each of said hollow head portions facing inwardly toward the corresponding member of the opposite wall assembly and provided at intervals with 35 openings in the outer surface thereof, headed connecting and spacing elements passing through the hollow upright portions of the T-shaped members and extending through said openings, the heads of said elements overlapping and resting 40 upon said flaring wings.

34. In an interior structure for buildings, a partition construction comprising, in combination, spaced wall assemblies of the built-up panel type each including a plurality of panels arranged in substantially edge to edge relation, and panel edge supporting strips each comprising a hollow box like member substantially T-shaped in cross section and having flaring wings at the base of the upright of the T, the panel edges being received between said wings and the hollow head flanges, each of said hollow head portions facing inwardly toward the corresponding member of the opposite wall assembly and provided at intervals with 50 openings in the outer surface thereof, tying and spacing elements passing through the hollow upright portions of the T-shaped members and extending through said openings, said elements being provided with heads and narrow necks at each end thereof, shoulders being provided on 55 said elements adjacent said necks, the heads of said elements overlapping and resting against said flaring wings, the necks occupying the hollow upright portions of the T-shaped members, and the shoulders abutting the inner walls of the cross portion of the T-shaped members.

35. In an interior structure for buildings, a suspended ceiling construction comprising a plurality of elongated main supporting members, hangers interlocking therewith and supporting 70 said members from the interior framework of the room, sheet metal panels provided with turned up edge flanges, so as to provide tray-like receptacles for sound deadening material of the like, the ends of said flanges provided with kerfs for interlocking 75 with said main supporting members.

36. In a wall assembly of the built-up panel type, a plurality of panels, a portion of the adjacent edges of certain of said panels adapted to abut each other and other portions of said edges to overlap adjoining panels, and T-shaped panel 5 edge supporting strips each having its head flanges embedded within the material of said abutting edges, whereby said strips are adapted to interlock with said panels, and the upright member of said supporting strips extending outwardly from the said abutting edges and adapted to be attached to a supporting structure

37. In an interior structure for buildings, a wall and ceiling sheathing assembly, of the built-up panel type, including a corner construction, 15 comprising the adjacent marginal panels of the ceiling sheathing and the wall sheathing respectively, said panels being disposed in planes normal to each other, and each having their adjacent edges offset from the line of intersection of said 20 planes, a cornice member arranged to cover the space between said adjacent edges and comprising a body portion provided along each side with an S-shaped reversely bent portion, forming a squared exposed margin for the cornice member 25 and also a concealed substantially U-shaped channel for the reception of the respective edges of said panels.

38. In an interior structure for buildings, a corner arrangement for wall and ceiling sheathing assemblies, said assemblies being of the built-up panel type and including panel edge supporting strips provided with flanges for interlocking with the adjacent edges of the panels and with substantially rectangular, box-like exposed portions adapted to conceal the edges of the panels, said corner arrangement comprising the adjacent marginal portions of said wall and ceiling assemblies which are disposed in planes at right angles to each other and the edges of which are 35 offset from the line of intersection of the two planes, a cornice member arranged to cover the space between said marginal edges and comprising a body portion provided along each side with an S-shaped reversely bent portion forming a 45 squared exposed margin for the cornice member which is of the same height as said exposed portion of said edge supporting strips, so as to form a continuous raised surface where said strips and said cornice meet, said S-shaped side portions of 50 the cornice also providing concealed substantially U-shaped channels opening outwardly in directions parallel with said respective intersecting planes, for the reception of the edges of said wall and ceiling assemblies. 55

39. As an article of manufacture, a sheet metal cornice member for application to the spaced margins of wall and ceiling panels disposed in intersecting planes, comprising, in combination, an intermediate molding portion adapted to be exposed when the cornice is installed, substantially S-shaped side portions formed on said intermediate portion providing squared exposed margins for the cornice member, and also concealed substantially U-shaped channels opening outwardly 65 in directions parallel respectively with the intersecting planes of the wall and ceiling panels and adapted to receive the spaced marginal edges of said panels.

40. The method of erecting a panelled interior 70 covering structure for the walls or ceiling of a room, which comprises the steps of suspending a series of parallel, spaced main supporting strips from the interior framework of the room, successively embedding the sharp flanges of the panel 75

edge supporting strips into the relatively soft material of successive ones of a row of insulating panels and interlocking the ends of said edge supporting strips with said main supporting strips.

5 41. An interior structure for building comprising, in combination, spaced wall and ceiling members, at least the exposed ones of which are composed of a plurality of panels, spacing and connecting elements between said spaced wall and ceiling members comprising elongated main supporting strips, the edges of said panels being kerfed, panel edge supporting members having relatively thin edges, said edges being inserted in the kerfs in said panel edges, and means for connecting said panel edge supporting members and said main supporting strips.

42. An interior structure for buildings comprising, in combination, spaced wall and ceiling members, at least the exposed ones of which are composed of a plurality of panels, each composed of relatively soft sound absorbing material, spacing and connecting elements between said spaced wall and ceiling members comprising elongated main supporting strips, panel edge supporting members having relatively thin edges, said edges being inserted in the edges of said panels, and means for connecting said panel edge supporting members and said main supporting strips. 5 10 15

ANDERS CHRISTIAN OLSEN. 15
